Assistant Examiner — Bryan N. Melvin

(57) **CLAIM**

The ornamental design for an accumulator charging apparatus as shown and described.

DESCRIPTION

1. Accumulator charging apparatus

1.1 : Front

1.2 : Back

1.3 : Left

1.4 : Right

1.5 : Top

1.6 : Bottom

1.7 : Perspective

1.8 : Perspective

1. Title of product of the present design: Accumulator charging apparatus. 2. Use of product of the present design: the product of the present design is used for charging on-board energy storage devices. 3. Reproduction showing the design: Reproduction 1.7. Reproduction 1.1 is a front elevation view of an accumulator charging apparatus, showing my new design; Reproduction 1.2 is a rear elevation view thereof; Reproduction 1.3 is a left side view thereof; Reproduction 1.4 is a right side view thereof; Reproduction 1.5 is a top plan view thereof; Reproduction 1.6 is a bottom plan view thereof; Reproduction 1.7 is a perspective view thereof; and, Reproduction 1.8 is a perspective view viewed from another angle thereof.

The portions of the design shown in broken lines form no part of the claimed design.

1 Claim, 8 Drawing Sheets
